Primary Examiner—Catherine R Oliver*(74) Attorney, Agent, or Firm*—Aka Chan LLP(57) **CLAIM**

The ornamental design for a portable electronic device case, as shown and described.

DESCRIPTION

FIG. 1 shows a perspective view of a first embodiment for a design for a portable electronic device case, where upper and lower case portions are assembled together.

FIG. 2 shows a front view of the first embodiment, where upper and lower case portions are assembled together.

FIG. 3 shows a rear view of the first embodiment, where upper and lower case portions are assembled together.

FIG. 4 shows a left side view of the first embodiment, where upper and lower case portions are assembled together.

FIG. 5 shows a right side view of the first embodiment, where upper and lower case portions are assembled together.

FIG. 6 shows a top side view of the upper case portion of the first embodiment.

FIG. 7 shows a bottom side view of the lower case portion of the first embodiment.

FIG. 8 shows a perspective view of the first embodiment, where upper and lower case portions are separated.

FIG. 9 shows a front view of the first embodiment, where upper and lower case portions are separated.

FIG. 10 shows a rear view of the first embodiment, where upper and lower case portions are separated.

FIG. 11 shows a left side view of the first embodiment, where upper and lower case portions are separated.

FIG. 12 shows a right side view of the first embodiment, where upper and lower case portions are separated.

FIG. 13 shows a perspective view of a second embodiment for a design for a portable electronic device case, where upper and lower case portions are assembled together.

FIG. 14 shows a front view of the second embodiment, where upper and lower case portions are assembled together.

FIG. 15 shows a rear view of the second embodiment, where upper and lower case portions are assembled together.

FIG. 16 shows a left side view of the second embodiment, where upper and lower case portions are assembled together.

FIG. 17 shows a right side view of the second embodiment, where upper and lower case portions are assembled together.

FIG. 18 shows a top side view of the upper case portion of the second embodiment.

FIG. 19 shows a bottom side view of the lower case portion of the second embodiment.

FIG. 20 shows a perspective view of the second embodiment, where upper and lower case portions are separated.

FIG. 21 shows a front view of the second embodiment, where upper and lower case portions are separated.

FIG. 22 shows a rear view of the second embodiment, where upper and lower case portions are separated.

FIG. 23 shows a left side view of the second embodiment, where upper and lower case portions are separated.

FIG. 24 shows a right side view of the second embodiment, where upper and lower case portions are separated.

FIG. 25 shows a perspective view of a third embodiment for a design for a portable electronic device case, where upper and lower case portions are assembled together.

FIG. 26 shows a front view of the third embodiment, where upper and lower case portions are assembled together.

FIG. 27 shows a rear view of the third embodiment, where upper and lower case portions are assembled together.

FIG. 28 shows a left side view of the third embodiment, where upper and lower case portions are assembled together.

FIG. 29 shows a right side view of the third embodiment, where upper and lower case portions are assembled together.

FIG. 30 shows a top side view of the upper case portion of the third embodiment.

FIG. 31 shows a bottom side view of the lower case portion of the third embodiment.

FIG. 32 shows a perspective view of the third embodiment, where upper and lower case portions are separated.

FIG. 33 shows a front view of the third embodiment, where upper and lower case portions are separated.

FIG. 34 shows a rear view of the third embodiment, where upper and lower case portions are separated.

FIG. 35 shows a left side view of the third embodiment, where upper and lower case portions are separated; and,

FIG. 36 shows a right side view of the third embodiment, where upper and lower case portions are separated.

The broken-line features in the figures are for illustrative purposes only and form no part of the claimed design.
